UNITED STATES PATENT OFFICE

JOHN H. McPIKE, OF ALTON, ILLINOIS

BOX FOLDING AND TAPEING MACHINE

Application filed May 10, 1924. Serial No. 712,223.

This invention relates to a certain new and useful machine for folding corrugated or other fiber boards or blanks and taping the edges together for the purpose of making car-
5 tons or packing receptacles for shipping and handling various classes of merchandise.

It has been found that packing boxes or cartons for shipping and handling various classes of goods can be made from wood fiber 10 by corrugating a thin sheet and pasting or gluing a plain sheet on either or both sides of the corrugated sheet, thus giving the product sufficient strength, elasticity, and pliability to make a container of a very high quality 15 for packing and shipping goods of various kinds. These boxes or containers have usually been made by cutting to size and "scoring" the box-board, that is, marking by an indentation along the line where the stock is to be 20 folded. At each corner of the box, the stock is slit and slotted so that it may be turned in at right angles to form the top and bottom of the box, respectively.

The usual method employed in the production 25 of such boxes or cartons is to form the board by hand into a box and join the abutting edges by means of a tape pasted firmly down upon each end, so as to hold the ends together.

I am aware, however, that a number of machines for folding boxes are in successful 30 operation, and I am also aware that taping folded boxes by machinery is not broadly new, but heretofore, as far as I am aware, 35 each of these processes has been performed either by single machines working independently or partly by machinery and partly by hand. It is an object of my present invention to provide, and I here show and will describe, 40 a combined machine for folding and taping boxes, thereby increasing production, while reducing the cost thereof, and making boxes of uniformly high quality.

My present application in its claims is directed, however, more generally to the folding mechanism of the machine, the taping mechanism thereof, while herein shown and described, forming more generally the subject-matter of a separate application.

Another object of my present invention is

the provision of a machine of the type stated that is efficiently capable of handling and folding into box-form box-blanks or stock of various sizes, shapes, and dimensions.

Another object of my invention is the provision of a machine of the type stated that is substantially entirely automatic in its action, requiring operators' attention only in delivering of the stock, cut to size, in bulk and installing upon the machine a reel of tape preferably sufficiently long to keep or maintain the machine in operation for several hours.

With the above and other objects in view, my invention resides in the novel features of form, construction, arrangement, and combination of parts hereinafter described and pointed out in the claims.

In the accompanying drawings (nine sheets),—

Figure 1 is a plan view of a sheet of stock 70 slit, slotted, and "scored" for box-formation;

Figure 2 is a plan view of a taped and folded box;

Figure 3 is a perspective view of a box before the top and bottom have been folded in 75 place;

Figure 4 is a perspective view of a complete box-folding and taping machine of my invention;

Figure 5 is an enlarged broken section, 80 showing cams, racks, and pinions for transmitting reciprocatory motion to certain of the moving or operating parts of the machine;

Figure 6 is a cross section of the box-folding portion of the machine, showing its wings and 85 clamps;

Figure 7 is an enlarged side elevation, partly broken away, of the box-folding portion of the machine;

Figure 8 is an enlarged perspective view 90 of a central portion of the machine broken away;

Figure 9 is a similar view of a rear portion of the machine;

Figure 10 is a side elevation of a rear portion 95 of the machine, showing the location and parts of the taping element;

Figure 11 is an elevation, partly broken away, of the indexing and adjusting discs of the taping portion of the machine;

Figure 12 is a detail cross section of the taping indexing and adjusting mechanisms;

Figure 13 is a side elevation of the taping mechanism;

5 Figure 14 is an enlarged perspective view, partly broken away, of the taping mechanism as a whole; and

10 Figure 15 is a fragmental sectional view of a slightly modified form of the folding portion of the machine.

15 Referring now more in detail and by reference characters to the drawings, which illustrate a preferred embodiment of my invention, A designates the base or frame of the machine, as a whole, B the receiving platform on which the stock C to be folded and taped is placed, D the folding element, and E the taping mechanism.

20 While any particular form of base or frame that is strong, sturdy, and rigid may be used, in my machine I preferably employ a base or table comprising a frame constructed of a plurality of longitudinal and lateral metal beams 3, which may be of channel, I-beam, or 25 other convenient form, firmly joined or united together at right-angles, so as to form a substantial, rectilinear structure, supported at a suitable height by end and intermediate preferably metal legs 4 braced by diagonal 30 members 5 firmly attached to the legs 4 and the side beams 3, the frame being braced and strengthened by intermediate longitudinal members 6, transverse members 7, and diagonal members, one of which latter is shown at 35 8. For the purpose of additionally strengthening the table and providing a bearing for certain of the moving parts of the machine, the table or base A is equipped with lateral truss-members 9 and cross or lateral rods 10 40 supported on upwardly extending side-brackets 11, the truss-members 9 and rods 10 being reinforced centrally by braces 12 up-standing from table A and, in turn, connected to the truss-members 9 by adjustable turn- 45 buckles 13. The base A is further equipped with a rigidly secured longitudinally disposed center-beam 14 extending throughout the entire length of the base intermediate its sides, which beam 14 not only serves to increase the rigidity of the base, but is the working center of the machine from which all lateral adjustments are made, for purposes shortly appearing. Suitably connected beams 15, firmly fixed to the legs 4, as best seen in 50 Figures 4 and 7, serve both to give the base additional rigidity and also as a supporting-frame for the bearings of the main driving shaft 16. It will thus be apparent that the structure of the base is such that it will withstand all the different stresses and strains that 55 may be imposed upon it in the usual operation of the machine, the necessity of a base of this extreme strength, stiffness, and weight arising from the fact that all the operating parts 60 of the machine are either superimposed upon

the base or depend from it, and upon such a base, all the operating parts will be maintained in perfect alignment and co-ordination with each other, effecting an efficient running of the machine with a minimum of friction.

70 To the moving parts of the machine, power is preferably delivered from an electric motor 17 (see Figure 7) by means of a belt 18 to a pulley 19 rigidly mounted on the main driving shaft 16, to which shaft power is transmitted from pulley 19 when desired through the medium of a suitable friction clutch, not shown. Rigidly attached to the main driving shaft 16, as best seen in Figure 7, 75 is a small spur gear 20 engaging, for the purpose of reducing the speed of the operating parts of the machine, with a larger gear 21 rigidly fixed to a counter-driving shaft 22 mounted for rotation on base A.

80 The stock C, as shown in plan in Figure 1, is in the form of a sheet of suitable material, such as, for instance, card or corrugated board, cut to size, scored, and slotted, that is to say, the edges of the stock have been suitably cut and slotted inwardly, as at 1, in alignment with the scoring, to provide the foldable top and bottom portions or flaps of the box, respectively. The stock C is disposed for folding cross-wise, so to speak, of the platform B, as best seen in Figure 4, and Figure 2 illustrates a box that has been folded and its free edges brought together and taped, as at 2, by our combined-folding and box-taping machine. Figure 2 also illustrates the 90 form in which the folded and taped box is delivered from the machine after the tape 2 has been applied, while Figure 3 shows a non-square or quadrilateral box-blank, such as the present stock C, that has been folded, taped, and delivered by the machine and the folded parts then drawn apart for the purpose of folding in the end-flaps preparatory to the 95 completion of the box.

100 As best seen in Figure 4, the receiving-plate-form B is in the form of a pair of preferably wooden floor-sections 23 suitably fixed to runners disposed for shifting movement on the table-frame upon opposite sides of center-beam 14 and for such purpose fixed to, and 105 shiftable laterally of the table-frame with, certain beams 36 hereinafter more fully described. The floor-sections 23 are each provided transversely with a grooved raceway 24, fitting in which for adjustment are brackets 110 25 supporting panels or wings 26, 26, and on the floor-sections 23 at the forward end of the machine is placed the unfolded stock or box-blanks C of Figure 1, cut to dimensions and 115 scored as desired in and depending upon the size and dimensions of the finished or completed box, the stock or blanks C being superposed one upon the other or stacked in a pile, as shown.

120 The taping mechanism E, I may here state, 125

occupies a fixed position near the lateral center of the base A adjacent the rear end of the machine and is disposed to deliver the tape to the folded stock at the exact working or lateral center of the machine. Hence, the box-blanks C to be taped must be so positioned upon the platform B that when fed forwardly and folded and their free edges brought together for taping, the joints will each correspondingly be in the lateral center of the table and carried in a straight line rearwardly to the taping mechanism E.

The proper location of the stock C upon the platform B being suitably determined so that, when its edges are folded over and brought together, the joint to be taped will be in approximately the exact lateral center of the beam 14, the guide-way-forming and stock-holding-wings or panels 26 are adjusted into sliding contact with the vertical sides of the stock-pile C and secured adjustably in such position by means of hand-screws 27 seated in the brackets 25 and adapted for engagement with the grooves of the raceway 24. In the present instance, suitable abutment-plates 29, 29, are removably or detachably secured to the wings or panels 26 for cooperation therewith in holding the stock C in a pile, the plates 29 being spaced from the surface of the platform 23 a distance slightly more than the thickness of a single sheet of stock, thereby permitting the lowest sheet C to pass rearwardly under them when such sheet is engaged by the conveyor-chains or feeding means, shortly to be described. I may state here that the abutment-plates 29 are employed for the convenience of the attendant only when box-blanks of relatively small sizes are being folded and taped; when larger size boxes are being made, the abutment-plates 29, 29, may be omitted, in which event a like function is performed by a pair of adjustable abutment-plates 30 supported on, and which may be oppositely adjusted laterally of the machine by means of, screws 31 supported at their ends in the forward set of brackets 11 and 12, the screws 31 having suitable gear-connections for rotation, partly shown at 32, with independently operable adjusting shafts 33 mounted in suitable bracket-bearings 34 and extending along the opposite longitudinal sides of the frame A, each shaft 33 being adapted for rotation in either direction, for purposes later appearing, by means of a removable crank 35.

Disposed upon the table A for movement crosswise or laterally of the table, and extending throughout in parallel spaced relation with and upon opposite sides of the center beam 14, are the previously mentioned preferably metal beams 36 having their upper longitudinal surfaces longitudinally grooved or channeled, as at 37, sufficiently wide and deep to freely carry endless belt conveyor chains 38—38 having rigidly at-

tached to their upper sides short, flat, straight-sided lugs 39 disposed at right angles to the axis of travel of the chains 38 and adapted to engage with and carry forward the bottom or lowest box-blank C in the pile disposed, as stated, upon the receiving platform-sections 23. Rigidly attached to and depending from the conveyor beams 36 at the forward end of the machine are brackets 40—40 supporting short shafts or axles 41, mounted for rotation upon which are sprocket wheels 42 having engagement with the conveyor-chains 38; and rigidly attached to and depending from the beams 36 at the rear end of the machine are similar bearing-brackets 40^a that, with other suitable brackets, as, for instances, bracket 43, support for rotation a transverse driving shaft 44. Loosely splined or feathered on the shaft 44 and straddled by the brackets 40^a to permit lateral adjustment of the beams 36 together with the parts attached or associated therewith, are sprocket wheels 45 having driving engagement with the conveyor-chains or belts 38. Fixed on shaft 44 and having driven connection by means of a chain or belt 46 with a sprocket-wheel 47 fixed on the driving-shaft 22, is a sprocket-wheel 49. As indicated, the beams 36 and the conveyor-chains 38 extend longitudinally the length of the machine, and hence it will be evident that, on rotation of shaft 22, the endless conveyor-chains 38 and their lugs 39 will be actuated to feed the box-blanks C successively rearwardly through the machine.

Fixed upon, and movable transversely of the machine with, the laterally shiftable beams 36, are bearing brackets 50, in which are mounted for both slidable and rotary movement splined shafts 51, and suitably fixed on the shafts 51 are oppositely disposed pairs of box-blank folding wings 52, 52, preferably of the form best seen in Figures 4, 6, and 7.

Keyed to the counter-driving shaft 22, is a cam 53 and follower 54 having engagement with a rack-bar 55, which, in turn, has meshing engagement with a gear 56 fixed on a transverse shaft 57 supported for rotation at its ends in suitable bearings, one of which is shown at 58, Figure 5. Centrally, the shaft 57 extends loosely through the laterally shiftable beams 36, as seen in Figure 7, and feathered upon the shaft 57 and enclosed in suitable housings 59 rigidly attached to the outer faces of the respective beams 36, are pinions or gears 60, 60, best seen in Figure 7, each having engagement with one face of respective two-faced racks 61 likewise suitably supported in position by the housings 59. Feathered on the shafts 51 are respective gears or pinions 62, which mesh with the other face of the respective racks 61, and hence it will be evident that, as shaft 22 is rotated, a reciprocator, or up and down, movement will be imparted to the rack-bar 55 and shaft 57 con-

sequently caused to rotatably move first in one direction and then in the other direction, and that as shaft 57 is so caused to rotatably move first in one direction and then in the other direction, the two-faced racks 61 will be caused to reciprocate and the shafts 51 consequently caused to rotate through an arc of approximately 180° first in one direction and then in the other direction. Thus, the folding-wings 52 will, in like manner, with their supporting shafts 51, be caused to swing or oscillate through an arc defined by the letters *a*—*b* first inwardly towards and downwardly upon the stock-blank C being conveyed by the chains 38 and then upwardly and outwardly from such blank C.

Intermediate their ends, the shafts 51 are each provided with a series of annular cogs forming circular racks 63, having meshing engagement with which are pinions 64 suitably housed upon the beams 36 and splined on a transverse shaft 65, in turn, suitably supported for rotation at its ends by table A and extending loosely through the beams 36. Fixed on shaft 65, is a gear 66 having meshing engagement with a rack-bar 67 held in place at its rack-end by a bracket-yoke 68 depending from the shaft 65 and fixed for reciprocatory movement at its other or lower end to an eccentric-strap 69 co-operating with an eccentric 70 keyed to the driving shaft 22. It will hence further be evident that, as shaft 22 is rotated and rack-bar 67 caused to reciprocate, the shafts 51 and their attached wings 52 will be given a reciprocatory movement longitudinally of the machine, and thus, as the conveyor-chains 38 are traveling constantly in one direction and successively feeding the box-blanks C rearwardly of the machine, the wings 52 both reciprocate rearwardly and forwardly of the machine and fold inwardly and outwardly relatively to the fed box-blanks C; and we may here state that the reciprocating movement of the wings 52 is so timed and synchronized both with relation to their oscillatory or swinging movement and to the feeding movement or rearward travel of the conveyor-chains 38 that the wings 52 oppositely open or swing outwardly through an arc of approximately 180° during their rearward reciprocating movement and oppositely close or swing inwardly through approximately the same arc during their forward reciprocating movement. Thus, as the successive box-blanks C are being fed rearwardly of the machine, the wings 52, in their described closing swinging movement, gradually engage the projecting ends of the successive box-blanks C and fold the same inwardly and downwardly, as best seen in Figure 7, and then open to release the particular folded box-blank C and so on throughout the operation of the machine.

35 Extending longitudinally of the machine

over the lateral center of the beam 14 and suitably rigidly supported at its ends by the forward and rear center brackets 12, with its lower edge sufficiently spaced from the table to allow free movement thereunder of the successive box-blanks C in folded form, is a fixed so-called guide-member in the form preferably of an elongated metal plate 71 adapted to correct any irregularity that may result in the described folding of the box-blanks C by the wings 52, so that the joints between the so folded end flaps of the respective successive box-blanks C shall be in the lateral center of the machine for uniform projection or feeding in a straight line to the taping mechanism E shortly to be described.

I have found from experience that, in order that the taping may be well and efficiently accomplished, it is substantially necessary that the portions or flaps of the successive box-blanks be completely flattened down after folding, and for this purpose we provide so-called pressing-clamps or pressers which are preferably in the form of elongated wooden members or beams 72—72 disposed centrally of the machine upon the opposite sides of and parallel with the guide-plate 71. Preferably, the upper marginal portion of the plate 71 is of increased dimensions, not only to give it strength and rigidity, but also to serve as a support for spaced bearings 73—73 for bell-cranks 74—74 having pivoted engagement at their lower ends with the presser-clamps 72. Pivotal connecting the bell-cranks 74 together at their upper ends is a link 75, which latter is pivotally connected at an end by a link 76 with the free end of an oscillating crank-arm 77 rigidly attached to a rocker-shaft 78 disposed in a horizontal position across the machine and supported in suitable bearings in the rear set of vertically disposed brackets 11—12. Near one end of the rocker-shaft 78, is rigidly attached a rocker-arm 79 connected by a pivotally joined link 80 to another rocker arm 81, rigidly, in turn, keyed to a second laterally disposed horizontal shaft 82, similarly supported for rotation by the rear center brackets 11, 12, as best seen in Figure 5. Keyed to shaft 82 is a pinion or gear 83 having meshing engagement with a rack 84 held in position by a suitable housing 85 and provided at its lower end with a cam-follower or roll 86 having co-operating engagement with a grooved cam 87 keyed to the counter-driving shaft 22. It will be evident that, as the countershaft 22 is rotated, the rack 84 will be reciprocated, the shafts 82 and 78 rotatably rocked first in one direction and then in the other, and the pressing clamps 72 successively shifted and rocked and thereby depressed or lowered upon and then removed from the successive folded box-blanks C as the blanks C are being fed rearwardly through the machine to the taping mechanism; and it follows that the rack 84

130

will be caused to reciprocate either constantly or intermittently in conformity to the contour of the groove of cam 87 and that correspondingly the shiftable or rockable clamps 72 will be lowered upon the successive folded box-blanks C and then immediately elevated therefrom or first lowered upon the successive folded box-blanks C, then allowed to remain in engagement therewith, and then elevated therefrom. The natural tendency of the folded box-blanks C is to return to unfolded or original condition; in my machine I hence prefer that the presser-clamps 72 remain in engagement with the successive folded-blanks C for a period of time, and, therefore, I have so designed the cam 87 to cause the rack 84 to make a full reciprocation and then rest, from which it follows that the presser-clamps 72 remain in pressing engagement with and hold the folded ends of the successive box-blanks C flattened down until the same are by the chains 38 rearwardly conveyed under the holding-guides or plates 88, best seen in Figures 4 and 7.

It is evident that, as the folding-wings 52 exert pressure on the successive stock C in the act of folding, the stock would be lifted bodily from a horizontal position if means of restraint were not provided. Hence, such disposition of the stock is restrained by fixed longitudinally disposed guides 89 having one end, as at 90, bolted to the abutment-plates 30, which guides provided straight sides or walls parallel to the longitudinal axis of the folding wings that not only prevent the fed stock from lifting at the axis of the fold, but, insure a straight fold exactly parallel to the edges to be taped. The guides 89 remain in fixed relation with the folding wings 52 and conveyor-beams 36 and since they are also in fixed relation with the abutment-plates 30, the mechanism for effecting lateral adjustments thereof to accommodate different size box-blanks or stock must all be coupled together to insure uniform and synchronous adjustments, all of which later appears.

In such manner, the machine being constantly in operation, the box-blanks C are first stacked upon the receiving-platform B, then successively fed to the folding and flattening means and in such feeding held and guided horizontally upon the table A by the guides 89, then uniformly folded for taping by the wings 52 in co-operation with the fixed guide-plate 71, then held in flat folded condition by the movable presser-clamps 72 and fixed clamps or plates 88, and then with the joint so formed fed to the taping mechanism for taping. I may state here that, as specifically illustrated in Figure 15, I prefer to facilitate the feeding of the successively folded box-blanks C by means of an auxiliary conveyor in the form of an endless chain 176, for accommodating which the center beam 14 is cut-away or apertured, as at 177, and lon-

gitudinally channeled or grooved, as at 178, rearwardly from the opening 177 to adjacent the taping mechanism D. This chain 176 is reeved upon an idler gear 179 suitably mounted for rotation on a bracket 180 fixed to the beam 14, a second idler gear 181, in turn, mounted for rotation upon a bracket 182 fixed to the beam 14, and a driving gear 183 fixed on a shaft 184 suitably mounted for rotation on the table-frame A. Suitably located and fixed on shaft 184, is a spur gear 185 having driven connection by means of a chain 186 with a larger gear 187 suitably fixed on the counter-driving shaft 22. Adjustably carried by the chain 176 for successively engaging the folded box-blanks C are suitably spaced engaging lugs 188 grooved upon their upper faces for accommodating and moving under the fixed guide-plate 71. By means of the chain 176, the successively folded blanks C are engaged intermediate the main conveyor chains 38 and the feeding of the box-blanks C in proper and uniformly folded condition to the taping mechanism facilitated. Preferably, to avoid any interference with the taping mechanism, the channel 178 is somewhat deeper adjacent the gear 181 than at its forward end adjacent the gear 179, as shown.

Referring again to Figure 2, it will be noted that the tape 2 has been applied to the folded box-blank or stock C at a point some distance from its opposite top and bottom sides and center, and in such connection I may here state that the distance from the center of the tape 2 to the right-hand margin of the box of Figure 2 is the length of a side of the box and the distance from the center of the tape 2 to the left-hand margin of the box of Figure 2 is the width of the box, the dimension from side to side of the blank defining the unfolded height of the box. It will be evident that when a quadrilateral box-blank, such, for instance, as the box-blank or stock C here shown, is folded flatwise together, the edges to be taped will be nearer one right or left margin of the folded stock than to the other. Only a square box may be so folded that the edges or ends to be joined would meet in the exact center. It will, therefore, be obvious that a folding and taping machine to be economically successful and efficient in the handling and production of boxes of various sizes and various shapes should be adjustable, so that the tape may be placed at any distance desired between the left and right margins of the box-blank or stock when folded flat together, as here shown in Figure 2. My present machine is of such type and capable of a wide range of adjustments on either side of the lateral center of the box, namely, the center beam 14, for handling, folding, and taping boxes of practically any shape, size or length. It will be clear, however, that if these various lateral adjustments should be inaccurately made by a careless or indifferent operator,

much stock would be wasted and the work performed by the machine unsatisfactory, and that the mechanism for effecting such lateral adjustments upon one lateral side of the machine must operate independently of the mechanism for effecting such lateral adjustments upon the opposite lateral side of the machine. It will also be clear that all lateral adjustments upon one side of the machine must be simultaneously made so that all the several parts to be adjusted on such respective side of the working center of the machine may function properly with a fixed relation to one another. Such mechanism in my machine will now be described, and since the mechanism for effecting adjustments on the one side of the central beam 14 are duplicated upon the other lateral side of the machine, a description of one such mechanism will suffice for both.

Mounted for rotation upon the table A is a series of transverse shafts 91 suitably spaced longitudinally of the machine, each shaft 91 being screw threaded for a part of its length, as at 92, and having engagement with a threaded bracket 93 rigidly fixed to the conveyor-beam 36, a beveled gear 94 rigidly keyed to the outer center of the shaft 91 having meshing engagement with a mating beveled gear 95 rigidly keyed to the longitudinally disposed rotatable shaft 33. As before stated, the shaft 33 is manually rotatable by the crank 35, and it will be apparent from the construction here described that, if the crank 35 is actuated in one direction, the particular beam 36, together with the parts associated therewith and carried thereby, will be actuated toward the center beam 14, and if the crank 35 is actuated in the opposite direction, the particular beam 36 and the parts associated therewith and carried thereby will be drawn from the center beam 14. As best seen in Figures 4 and 7, the gears 32 fixed upon the screws 31 carrying the abutment-plates 30 are connected for actuation by means of beveled gears 96 and 97 and diagonally disposed shafts 98 with the adjusting shafts 91, and thus in a simple, efficient manner, on actuation of the main adjusting shafts 33 disposed at the opposite sides of the frame, the conveyor chains 38, the abutment plates 30, the restraining guide-clamps 89, and the folding wings 52 upon the opposite sides of the center-beam 14 may be independently adjusted laterally toward or from the center beam 14 to accommodate for feeding and folding box-blanks of various sizes and dimensions, so that when folded and their free edges brought together for taping and irrespective of the size and dimensions of the box-blank, the edges thereof to be taped will be brought flatwise in abutting relation in the exact lateral center of the machine.

In the foregoing description, I have described the various parts of the machine,

which effect successive folding of the box-blanks C, the free edges of each thereof to be taped being folded and brought together to approximately flatwise abut in a straight line and in the exact lateral center of the machine and as so folded delivered or fed by the conveyor-chains 38 and 176 to the taping element E, now shortly to be described. The commercial and economic value of any automatic machine naturally depends upon its capacity, and its capacity depends upon its ability to produce uninterruptedly or uninterrupted, so that the product produced by it flows steadily through it in a constant stream, each operation taking place progressively, untouched by human hand and developing from the raw material into the finished product in the shortest possible time. In my present machine, the conveyor 38, when feeding, runs continuously in one direction, carrying the stock C rearwardly from the receiving platform through the process of folding and taping without a pause. Since the tape must be placed upon the folded box throughout its lateral center and at various distances from its longitudinal center, as illustrated in Figure 2, it is evident that exact and definite adjustments of the taping element be provided for. I have provided for all longitudinal adjustments for placing the tape by the lateral adjustments of the conveyor and folding elements relatively to a fixed center, as before described. The adjustments for placing the tape in the lateral center of the folded box-blanks of various shapes and sizes are provided for, as shortly appearing, by adjustments wholly within the taping element E, which is built preferably as an integral part of the combined machine, although it is evident that either the folding element or taping element would perform their respective functions independently of each other, the conveyor being common and a necessary part of each element.

The successful operation of a taping mechanism for boxes of various sizes and various shapes involves the solution of two unique problems. The first, that of causing the tape to be placed upon the stock at the exact point desired has been referred to above and will be further elucidated as the taping element is explained. The second involves means for maintaining the adhesive at a temperature and a degree of fluidity or viscosity that will insure the firm adhesion of the tape to the box. It is well understood that the fluidity or viscosity of liquids is affected both by temperature changes and the amount of humidity in the atmosphere. I have found by experience that, if the tape receives the proper degree of moisture from the moistening roll on days when the atmosphere is hot and dry, the tape must be applied as quickly as possible after leaving the moistening roll; on the other hand, when the atmosphere has a high

degree of humidity, moisture will be added by the atmosphere. Therefore, to obtain the proper degree of moisture to insure effective adhesion of the tape, I have found it necessary to provide means for regulating the length of time the moistened tape is exposed to the atmosphere between the time it is moistened by the roll and its application to the box-blank. I have, also, found that this adjustment of the machine must be made during its operation as often as a material change in humidity or temperature takes place.

The taping mechanism E is located, as before stated, adjacent the rear end of the machine, disposed to deliver the tape to the successive folded box-blanks C longitudinally of the machine in the lateral working center thereof, and is best seen in Figures 9, 10, 11, 12, 13 and 14.

Rigidly attached to the frame A of the machine, is a bracket 99, suitably supporting for rotation a so-called hollow shaft 100, and disposed for rotation for the most part within the hollow shaft 100, is a second or so-called solid shaft 101, which shafts are yieldingly held against rotatory movement by a coiled spring 172 having engagement or attachment at its ends to the shaft 100 and to the bracket 99, as best seen in Figure 14.

Rigidly fixed to the shaft 100, is a radially disposed rocker or puller-arm 102, to the outer or free end of which is rigidly fixed a downwardly projecting curved portion or housing 103 supporting a pair of opposed sets of suitable preferably yielding or spring tape-gripping fingers 104. To and between the fingers 104, tape 105 of any suitable width and quality is supplied and threaded from a reel thereof disposed and securely held by lateral fasteners 106 between two holding disks 107 mounted for rotation upon a stub-shaft carried at one end of a bracket-arm 108 supported intermediate its ends for rotatory movement upon a bracket 109 upstanding from the table A. A duplicate pair of reel-holding disks 107^a is carried for rotation by the other end of the bracket-arm 108, so that, when the supply of tape from one reel is exhausted, the duplicate reel may be switched into position, either pair of said reel-holding disks being held in tape-supplying position by a spring actuated fastener-bolt 110 adapted to engage a keeper 111 carried by the disks, all as best seen in Figure 9.

The tape 105 is first drawn from the reel by hand and then threaded under an idler-roll 112, then under a moistening reservoir supplied preferably by a tank 114, then around an idler-roll 115, then beneath a guide-roll 116, and then over the moistening roll 117 with the gummed surface contacting with the periphery of the moistening-roll and receiving moisture therefrom. The tape 105 is then passed under an idler-roll 118, where the tape is reversed so as to expose

the moistened side thereof to the atmosphere without contacting with the surface of the several rollers. The tape 105 is then passed over an idler-roll 119 supported on a standard 120 and from roll 119 threaded between the opposed sets of fingers 104, where the tape is held taut and under tension and gripped by a so-called gripping-member 121 held by means of slots and bolts 122 for limited sliding movement upon the rocker-arm 102 and adapted at one end to clamp the threaded tape 105 against an upwardly projecting portion 123 of the finger-housing 103. As best seen in Figure 14, the gripping-member 121 is normally held yieldingly in retracted position out of engagement with the tape by means of a retracting-spring 124 and is positively actuated to engage or grip the tape against the housing-portion 123 by means of a rocker-arm 125 radially projecting from and fixed to the said so-called solid shaft 101. It will be evident that, following such arrangement, the rocker-arm 125 will also be yieldingly held by the spring 172 both in and returned to normal position.

Mounted for rotatory movement in a suitable bearing 126 supported by the bracket 99, is a shaft 127, fixed upon which is a member 128, best seen in Figures 13 and 14. As there shown, the member 128 is of somewhat skeleton form and surrounds for relative movement the tape-tensioning housing 103, and through which member the housing 103 is adapted to reciprocatorily swing rearwardly downwardly and forwardly upwardly through an arc of approximately 32°. The member 128 carries a knife-blade 129, which is normally, or when in elevated position, disposed rearwardly of the fingers 104, as seen in Figure 13, the member 128 being also as more fully later appears, adapted for swinging movement relatively to the tensioning-housing 103 to bring its carried blade 129 into tape-shearing or cutting co-operation with a fixed or stationary knife-blade 130 disposed under the member 128 and supported by a cross-member 131 carried for adjustment, for purposes later appearing, by the bracket 99, as best seen in Figure 13.

Also suitably carried for rotation by the bracket 99 and disposed rearwardly of the co-operating knife-blades 129 and 130, is a preferably knurled or otherwise peripherally roughened presser-roller 132, co-operating in stock-feeding relation with which is a roller 133 suitably supported by rotation upon a bracket 134 pivotally supported for adjustment on the frame A by an arm 135.

It will be apparent that without means for adjusting the feed of the tape and the cut lengths of the tape, the tape will always be delivered to the stock at one point irrespective of the size or height of the boxes being taped, and hence the taping of different size boxes would require different size machines.

In my machine, however, provision for adjusting the feed of the tape and the cut lengths of the tape to all sizes and heights of boxes is made, and such means and the means for actuating the tape-gripping, pulling, and cutting members will now be described.

Also suitably supported by the bracket 99, is a short journal 136 for a rotatable sleeve 137. As best seen in Figure 12, one end of the sleeve 137 is provided with an annular flange 138 and the opposite end thereof screw-threaded for receiving a nut 139 adapted, when threaded upon the sleeve 137, to clamp firmly together the several intervening members or disks, now to be described, mounted on the sleeve 137, so that said members or disks shall rotate with the same angular velocity and in fixed relation to each other.

Mounted on the sleeve 137 is a pinion-gear 140 having driven connection by means of a chain or the like 173 and a train of gearing designated as a whole as 174, see Figure 9, with a sprocket-gear 175 fixed on the conveyor driving-shaft 44.

Also mounted on sleeve 137 and fixed to the gear 140, is a graduated or so-called index disk 141; and disposed on sleeve 137 in flatwise abutting relation with the disk 141, is a smaller disk 142 provided upon its periphery with a pair of outwardly projecting so-called cam-noses 143, 144, and also with an outwardly projecting index finger or pointer 145 adapted in co-operation with and relatively to the graduated disk 141 to indicate the angularity of the disk 142 relatively to the disk 141 for the purpose of effecting adjustments of the pulling fingers 104 and gripping-member 121 in their tape engagements to suit or correspond with boxes of various sizes.

Also disposed upon the sleeve 137 in flatwise abutting relation with the disk 142, is a second graduated or index disk 146 sustaining a fixed relation to the larger graduated disk 141 by means of a hub-sleeve 147 and dowel pins 148, as best seen in Figure 12.

Further disposed upon the sleeve 137 in flatwise abutting relation with the second dial disk 146 is a fourth disk 149 provided upon its periphery with an outwardly projecting index-finger 149^a and with one or more preferably removable cam-grooves 150 adapted for engagement by a roller 151 carried in the end of the rocker arm 152 rigidly attached to the shaft 127, which shaft 127 is adapted for rotation under the torsional tension of a helical spring 153 coiled about the shaft 127 and one end of which is attached to a collar 154 and the other end of which is attached to the shaft bearing 126. Rigidly attached to the hollow shaft 100, is a pawl 155 adapted for actuation by the cam-nose 144 of disk 142, and rigidly fixed on the solid shaft 101 is a second pawl 156 adapted for actuation by the cam-nose 143 of the disk 142. It will

now be evident that, on rotary actuation of the disk 142, the pawl 156 will be tripped, thereby effecting a yielding rocking against the pull of spring 172 of the arm 125 and the gripping plate or member 121 actuated, in turn, to grip the tape against the finger-housing portion 128; at the same time, the pawl 155 will be tripped by the cam nose 143, thereby likewise effecting a yielding rocking against the pull of spring 172 of the arm 102 and consequently a downwardly and rearwardly rocking also of the finger-housing 103 and its carried fingers 104, the free end of the tape 105, in such movement, being carried between the now spaced cutting blades 129 and 130 and deposited lengthwise upon the joint in the stock C being fed or conveyed between the co-operating rollers 132 and 133.

It will also be evident that, when the roller 151 drops into a cam-groove 150, the shaft 127 will be instantly caused to rotate under the torsional tension of the spring 153, in turn, effecting a rocking of the knife carrying member 128, upon which movement the movable blade 129 is carried into tape shearing or cutting co-operation with the fixed or stationary blade 130 and the tape 105 thereby cut at the exact point desired after the same has been fed, as described, to and upon the joint in the box-blank C traveling between the rollers 132 and 133, which rollers are caused to rotate under frictional engagement with the traveling stock.

It will be noted that the cam-noses 143, 144, are symmetrical or alike on their lifting or pawl-tripping faces and thereby effect substantial simultaneous operation of both the gripping member 125 and the puller-frame or housing 103, while their opposite faces are unlike, the cam-nose 143 being shaped or formed, as shown, to release the gripping-actuating arm 125 in advance of release of the puller-arm 102 by the other cam-nose 144, both of which, upon such release return to normal position by the pull of their shaft-engaging spring 172, the gripping-plate or member 121 being at the same time retracted by the spring 124. The purpose of such release of the tape-gripping and pulling members is to prevent any pulling of the tape from its supporting reel on the return movement of said members, as will be obvious.

As best seen in Figure 14, the stationary knife supporting-member 131 is preferably adjustable by means of an adjusting-screw 120 157 and its co-operating-mechanism 158. The tension or grip of the fingers 104 upon the tape is adjustable by means of an adjustment-lever 159 supported by their housing 103, and it will be clear that, when the puller-housing 125 103 and its carried fingers 104 are yieldingly returned to normal by the action of the helical spring 172, the tape 105, having been already adhered to the moving stock, continues to be drawn from the reel through the puller-frame 130

103 and guide-wires 104 until a sufficient length has been supplied to suit the size box being taped when the rocker arm 152 drops into one of the cam grooves 150, causing the cutting mechanism to operate as is above described.

After the tape is cut to length and applied, it must be smoothly disposed over the surface of the taped edges of the box. This is properly performed by two rotatable brushes 160, 160, rigidly keyed to transverse shafts 161, 161, suitably supported in bearings 162, 162, and driven by the sprockets 163, 163, actuated by the chain 173, and I may add that the idler-
10 roll 133 positioned beneath the stock and cooperating with the knurled roller 132 is preferably vertically adjustable by means of a wedge and screw adjustment, not shown, for increasing or decreasing the pressure applied
15 to the tape as it passes between the rollers 132 and 133.

Reverting now to the indexing assemblage best seen in Figures 11 and 12, normally the several members of the assemblage rotate continuously in fixed angular relation to one another, which fixed relation is predetermined by the height-dimension of the particular box-blanks or stock being taped. It will be noted that the dials 141 and 146 are graduated in inches, half-inches, and quarter-inches from zero to sixty inches. The purpose of such graduation is to serve as an index for effecting pulling and cutting of the tape to proper length and for placing the tape at the proper point on the successive folded box-blanks. The two graduated dials 141 and 146 carry identical graduations up to sixty and serve as an index for setting the taping mechanism to handle stock up to a size measuring
20 sixty inches overall in height or stock of substantially any even division of sixty inches in overall height. For larger sizes a larger machine of identical parts and identical functions may be constructed, and it will be apparent from the foregoing description that the tape will be placed upon the moving stock at approximately the exact moment the cams 143, 144 engage and trip the pawls 155, 156, and as the taping element E, the folding element D, and the stock feeding means operate in fixed timed relation with each other, the tape will always be placed at the same and exact point so long as the cams 143, 144 bear
25 the same timed relation to the other moving parts of the machine.

The above statements apply with equal and exact force to the cutting mechanism. Therefore, in order to vary the point of contact of the tape with the successive folded box-blanks C and also to vary the point at which the tape is severed, it is necessary to change the timed relation of the cams 143, 144 and the cam grooves 150 with the other moving parts of the machine. The dial-faced disks
30 141, 146, remain always in a fixed timed re-

lation with the moving mechanism of the entire machine. These disks, as before stated, are graduated from zero to sixty inches, which means that when they make one complete revolution, the conveyor-chains 38 have traveled sixty inches. When the disks 141, 146 make a half revolution, the conveyor-chains 38 have carried the stock forward thirty inches, and so on, in like proportion. If now the plain disks 142, 149 be rotated relatively to the dial disks 141, 146, so that their index fingers 145, 149 point to zero and 30 on their respective cooperating graduated disks 141, 146, and if the plain disk 149 had only one cam-groove 150, the tape would be placed first at zero and then at every sixty inches. Now, if the plain disk 149 be provided, as in the present instance, with two cam-grooves 150 diametrically opposite, the tape will be placed and cut at every thirty
35 inches from the point at which they are set. Four cam-grooves 150 disposed 90 degrees apart would effect a taping and cutting at intervals of fifteen inches, and so on.

Observing Figure 2 of the drawings, it will be evident that the tape must be placed at an exact and definite distance from the front edge *s* of the folded stock. In the present instance, let it be assumed that the lugs or slats 39 of the conveyor chains 38 are spaced thirty inches, that the overall height dimension, that is to say, the distance from the front edge *s* and the rear edge *t* of the particular box-blank C there shown, is twenty-five inches, and that the end flaps the portions *w* to be folded in, that is to say, the forward portion *w* of the blank between the edge *s* and the scoring line *y* and the rearward portion *x* of the blank between the edge *t* and the adjacent scoring line *z*, are each five inches in width, so that the finished height of the box, with its top and bottom flaps folded in, that is to say, the portions *w* of the box intermediate the scoring lines *y*—*z*, is fifteen inches; consequently, the index finger 145 of the tape-placing disk 142 will be set at twenty inches, so that, when the stock has moved ten inches rearwardly through the taping mechanism, or an aggregate distance corresponding substantially to the width of the end flap *w* of one blank and the forward flap *x* of the succeeding blank, the tape will be applied. The length of the tape to be measured and cut is fifteen inches, and hence the tape pulling and cutting mechanism will be set to correspondingly pull or measure and cut the tape. Thus, at every thirty inches' travel of the conveyor-chains, the tape will be applied and cut.

By loosening the clamping nut 139 on the index-assembly sleeve 137, the plain disks 142 and 149 may be rotated to any desired position with relation to the dial disks 141, 146; by then screwing on or tightening the clamping nut 139, the entire indexing assemblage
125

rotates as a unit. It will be understood that the plain disks 142, 149, may be provided with any number of cam-noses and cam-grooves equally spaced apart at even divisions of sixty; by so doing, and with the slats 39 correspondingly spaced, substantially any size or shape box-blank or stock may be taped.

Should it be required to fold and tape boxes 10 of more than sixty inches of overall height, this result may be obtained by decreasing the speed of the indexing mechanism relatively to the conveyors. In short, by such adjustments in the timed relation of these two 15 mechanisms, the present machine may be well described as a universal box-folding and box-taping machine.

An important and valuable feature of my 20 machine is the automatic control and temperature regulation of the moistening fluid. The fluid supply tank 114, which is of large capacity, is capable of hermetic sealing by a screw-threaded cap 164 and so positioned for communication by a vertically disposed feed-pipe 25 165 having a stop flow valve 166 with the reservoir 113, into which the moistening fluid or water flows. Beneath the reservoir 113 is an electric or gas heater 167 of any suitable kind that may be closely regulated to a temperature 30 that will maintain the water or adhesive at a proper consistency or viscosity. An air-tight conduit 168 is vertically disposed through the bottom of the supply tank 114 and extends upwardly to near the top 35 of said tank, the lower end extending downwardly to the desired water level into the open receptacle or reservoir 113, both ends being open. It is, therefore, evident that, as the fluid sinks below the lower open end of the 40 conduit 168, air will be permitted to enter the supply tank 114 thus breaking the hermetic seal and causing the water to flow into the reservoir 113 until the water level rises sufficiently high to stop the flow of air which, 45 in turn, effects a stoppage in the flow of water—hence a constant level is automatically maintained in the reservoir 113.

I have found by experience that the 50 gummed surface of the tape after being moistened is extremely sensitive to heat and moisture. I have also found by experience that corrugated box-board and other box material varies greatly in absorbent characteristics and that, in order to insure efficient and 55 satisfactory adhesion of the tape to the stock, the viscosity of the adhesive must be changed to suit the atmospheric and weather conditions, as well as to suit various classes of stock. By means of the heating element 167 I 60 maintain the moistening fluid at a proper consistency for average conditions, and then by raising or lowering the idler roll 119 upon the standard 120, the roller 119 being adjustable up or down upon the standard 120 65 by means of a friction-clamp 169 over a rel-

atively wide range, I am able to expose the moistened tape for a longer or shorter period of time before it is applied to the folded box-blank, thus obtaining maximum results.

It is evident that the output of the machine 70 per unit of time depends upon the speed of the conveyor, which, in my machine, is relatively high, necessitating a quick return of the tape-placing mechanism. The return of such mechanism is effected, as described, by the torsional tension of the spring 172. This 75 spring 172 is of such strength, however, that it recoils with considerable force and, if not opposed, would impose harmful strain and shock upon the adjacent mechanism. To obviate this, I have provided a pneumatic shock absorber consisting of a pivotally mounted cylinder 170 provided with an adjustable air vent 171 having a piston reciprocable 80 therein, which piston is operatively connected to a rocker-arm, not shown, located intermediate the ends of the shaft 100 and rigidly attached thereto. When the spring recoils, it is evident that the shock will be absorbed by the air cushion between the piston and cylinder heads.

As best seen in Figure 9, the shiftable beams 85 36 are provided in the rear portion of the machine with side plates 189, which, at their upstanding marginal portions, function to 90 guide the folded and taped box from the machine.

My machine is automatic in its operations and is exceedingly efficient in the performance of its intended functions, and I am aware 100 that changes in the form, construction, arrangement, and combination of the several parts of my machine may be made and substituted for those herein shown and described without departing from the nature and principle of my invention.

Having thus described my invention, what I claim and desire to secure by Letters Patent is:

1. A box-folding machine including, in combination, means comprising oppositely disposed wings swingably and reciprocatorily movable for engaging and folding the stock, and continuous feeding means for conveying the stock to and from the folding-wings.

2. A box-folding machine including, in combination, a pair of spaced rack shafts rotarily and slidably movable, oppositely disposed wings fixed to and movable with the shafts, mechanism for effecting both rotatory and reciprocatorily movement of the shafts for swingably and reciprocatorily actuating the wings to engage and fold the stock, and means for conveying the stock to the wings.

3. In a box-folding machine, means for folding the stock, and an oscillatory presser-clamp shiftable longitudinally of the machine for engaging the folded stock.

4. In a box-folding machine, means for successively conveying the stock through the

- machine, means for folding the fed stock, and presser-clamps shiftable during feeding movement of the conveying means for engaging the folded fed stock.
5. In a box-folding machine, means for conveying the stock through the machine, means for folding the fed stock, presser-clamps for engaging the folded fed stock, and mechanism for shiftably actuating the presser-clamps during feeding movement of the conveying means.
6. In a box-folding machine, means for conveying the stock through the machine, oppositely disposed members for engaging the fed stock for oppositely folding portions thereof, a pair of presser-clamps for engaging the folded fed stock, and means for shiftably actuating the clamps simultaneously during feeding movement of the conveying means.
7. In a box-folding machine, means for conveying the stock through the machine, oppositely disposed members for engaging the fed stock for oppositely folding portions thereof, a shiftable pair of presser-beams for engaging the folded fed stock, and means for shiftably elevating and lowering the presser-beams simultaneously during feeding movement of the conveying means.
8. In a box-folding machine, means for conveying the stock longitudinally through the machine, oppositely disposed members for engaging the fed stock for oppositely folding portions thereof, a shiftable pair of elongated presser-beams disposed longitudinally of the machine for engaging the folded fed stock, and means for shiftably elevating and lowering the presser-beams during feeding movement of the conveying means.
9. In a box-folding machine, means for conveying the stock through the machine, means for folding the fed stock, a fixed member for guiding the folding of the fed stock, and shiftable presser-clamps for engaging the folded fed stock upon opposite sides of said fixed member.
10. In a box-folding machine, means for conveying the stock through the machine, oppositely disposed members for engaging the fed stock for oppositely folding portions thereof, a fixed member disposed intermediate the folding members for guiding the folding of the fed stock, shiftable presser-clamps for engaging the folded fed stock upon opposite sides of said fixed member, and mechanism for shiftably actuating the presser-clamps.
11. In a box-folding machine, means for conveying the stock longitudinally through the machine, oppositely disposed members for engaging the fed stock for oppositely folding portions thereof, a fixed member disposed longitudinally of the machine intermediate the folding members for guiding the folding of the fed stock, shiftable presser-clamps for engaging the folded fed stock on opposite sides of said fixed member, means for shiftably actuating the presser-clamps during feeding movement of the conveying means, and fixed clamps for maintaining the fed stock in folded pressed condition when released by the folding members and presser-clamps.
12. In a box-folding machine, a stock support, means upon the support for maintaining the stock in a pile, conveying means traveling under the pile for feeding the stock from the pile through the machine, and means comprising swingable members actuatable during feeding movement of the conveying means for folding the fed stock.
13. In a box-folding machine, a stock support, means upon the support for maintaining the stock in a pile, conveying means traveling under the pile for feeding the stock from the pile through the machine, means comprising swingable members actuatable during feeding movement of the conveying means for folding the fed stock, and means for retaining the stock horizontally upon the support while being acted on by the folding means.
14. In a box-folding machine, a support for stock of various dimensions to be folded, in combination with means comprising conveyors laterally shiftable relatively to each other for conveying the stock of various dimensions through the machine, and means comprising swingable members also laterally shiftable relatively to each other for folding the fed stock of various dimensions.
15. In a box-folding machine, a support for stock of various dimensions to be folded, means including conveyors laterally shiftable relatively to each other for conveying the stock through the machine, means including oppositely disposed swingable members laterally shiftable relatively to each other for folding the fed stock, and mechanism for shiftably adjusting the conveying and folding members in accordance with the dimensions of the particular stock being folded.
16. A box-folding machine including, in combination, a support for stock of various dimensions to be folded, beams oppositely shiftable upon the support, means comprising members mounted for swingable movement upon the beams for folding the stock, means comprising conveyors traveling upon the beams for feeding the stock to the folding means, and means for shifting the beams relatively to each other for adjusting the folding-members and conveyors in accordance with the dimensions of the particular stock being folded.
17. A box-folding machine including, in combination, a support for stock of various dimensions to be folded, adjustable means for maintaining stock of respective various dimensions in a pile upon the support, beams oppositely shiftable upon the support, means

- comprising members mounted for swingable movement upon the beams for folding the stock, means comprising conveyors traveling upon the beams and under the respective pile for feeding the stock from the pile to the folding means, and means for shifting the beams relatively to each other for adjusting the folding-members and conveyors in accordance with the dimensions of the particular stock being folded.
18. A box-folding machine including, in combination, a support for stock of various dimensions to be folded, adjustable means for maintaining stock of respective various dimensions in a pile upon the table, beams oppositely shiftable upon the support, means comprising members mounted for swingable movement upon the beams for folding the stock, means comprising conveyors traveling upon the beams and under the respective pile for feeding the stock from the pile to the folding means, and mechanism comprising threaded rods having engagement with the beams and with the support for shifting the beams relatively to each other for adjusting the folding members and conveyors in accordance with the dimensions of the particular stock being folded.
19. A box-folding machine including, in combination, a support for stock of various dimensions to be folded, adjustable means comprising shiftable abutment-plates for maintaining stock of respective various dimensions in a pile upon the table, beams oppositely shiftable upon the support, means comprising members mounted for swingable movement upon the beams for folding the stock, means comprising conveyors traveling upon the beams and under the respective pile for feeding the stock from the pile to the folding means, and mechanism comprising threaded rods having engagement with the beams and with the support for shifting the beams relatively to each other for adjusting the abutment-plates, feeding members, and conveyors in accordance with the dimensions of the particular stock being folded.
20. In an automatic box-folding machine, conveying means traveling longitudinally of the machine for feeding the box-blank through the machine, and means including a pair of opposed wings movable longitudinally, and also swingable transversely, of the machine during and concurrently with feeding movement of the conveying means for folding side portions of the blank into edgewise abutting relation over an intermediate portion of the blank.
21. In a box-folding machine, in combination, means comprising endless conveyors for feeding the stock through the machine, and means comprising members swingably and reciprocatorily actuatable during move-
ment of the conveying means for folding the fed stock.
22. In a box-folding machine, in combination, means comprising endless conveyors for feeding the stock through the machine, means comprising members actuatable for folding the fed stock, and mechanism for effecting both feeding movement of the conveying means and swingable and reciprocatorily actuation of the conveying members during feed-
ing movement of the conveyors.
23. In a box-folding machine, in combination, means comprising endless conveyors for feeding the stock through the machine, oppositely disposed members actuatable for folding the fed stock, shiftable presser-clamps for engaging the folded fed stock, and mechanism for effecting feeding movement of the conveying means and both swingable and reciprocatorily actuation of the folding members and shiftable actuation of the presser-members during feeding movement of the conveying members.
24. In an automatic box-folding machine, a support for the box-blank to be folded, a traveling conveyer for feeding the blank through the machine, a pair of opposed members movable longitudinally and concurrently swingable transversely of the machine for folding side portions of the blank into edge-
wise abutting relation over the intermediate portion of the blank while the blank is being fed by the conveyer, and mechanism for actuating the conveyer and the folding members in timed relation.
25. A box-folding machine including, in combination, a support for the stock to be folded, a traveling conveyor for feeding the stock, swingably movable members for oppositely folding the stock while the stock is being fed by the conveyor, and means for synchronously actuating the folding members transversely and the conveyor longitudinally of the machine.
26. A box-folding machine including, in combination, a support for the stock to be folded, swingably reciprocatorily movable members for folding the stock, flattening members for engaging the folded stock, a traveling member for conveying the stock to the folding and flattening members, and mechanism for actuating the folding, flattening, and feeding members in timed relation.
27. In a box-folding machine, means including a wing movable longitudinally and swingable transversely of the machine for folding the stock upon itself, and means for feeding the stock while being folded by the wing.
28. In a box-folding machine, means including a wing swingable through an arc of approximately 180° for folding the stock upon itself, and means for feeding the stock while being folded by the wing.

29. In a box-folding machine, means including a wing swingable through an arc of approximately 180° and reciprocatorily movable longitudinally of the machine for folding the stock upon itself, and means for feeding the stock while being folded by the wing. 70
30. In a box-folding machine, means including a pair of wings each swingable through an arc of approximately 180° and reciprocatorily movable longitudinally of the machine for oppositely folding the stock upon itself, and means for feeding the stock while being folded by the wings. 75
31. In a box-folding machine, means for feeding the stock, means for folding the fed stock, and means including a presser-clamp shiftable during movement of the feeding means for engaging the folded fed stock. 80
32. In a box-folding machine, means for feeding the stock, means for folding the fed stock, means including a shiftable presser-clamp for engaging the fed and folded stock, and means for adjustably regulating the period of engagement of the clamp with the folded fed stock. 85
33. In an automatic box-folding machine, means including opposed swingable wings for folding side portions of the box-blank into edgewise abutting relation over the intermediate portion of the blank, fixed guide-means disposed upon the machine intermediate the wings for the free edges of the folded side portions of the blank, and means for feeding the blank through the machine with its intermediate portion under said guide-means. 90
34. In an automatic box-folding machine, means including opposed swingable wings for folding side portions of the box-blank into edgewise abutting relation over the intermediate portion of the blank, an upstanding fixed guide-plate disposed longitudinally of the machine intermediate the wings for the free edges of the folded side portions of the blank, and means for feeding the blank through the machine with its intermediate portion under said plate. 95
35. In a combined box-folding and taping machine, in combination, a support for the stock to be folded, means for folding the stock, means for taping the folded stock, a conveyor common to the folding and taping for successively feeding the stock to and through the folding means and taping means, and mechanism for actuating the folding means, taping means, and conveyor in timed relation. 100
36. In a combined box-folding and taping machine, in combination, a support for the stock to be folded, means including movable members for folding the stock, means for taping the folded stock, and continuous means common to the folding and taping means for successively conveying the stock 105
